HOCKEY STICK

John Roy Yerger, Lititz, Pa.

Application January 4, 1946, Serial No. 639,019

6 Claims. (Cl. 273—67)

1

My invention relates to hockey sticks.

One purpose of the invention is to produce a durable well-balanced hockey stick which will insure safety, comfort and poise to the player and reduce the danger of breakage due to the rough usage which a hockey stick ordinarily undergoes.

A further purpose is to reinforce the joint between a hockey stick handle and the rear and upper part of the blade of the stick.

A further purpose is not only to strengthen the joint of a handle and blade by overlapping parts which have their grains in different directions but additionally to reinforce the joint by the selection and arrangement of the thicknesses of the overlapping parts, and particularly by tapering in selected ways the parts which overlap, so that they may perform their strengthening functions to the best advantage.

A further purpose is to mortice and tenon a terminal of a hockey stick handle and the blade with which it is used, tapering the handle rearwardly and upwardly, and to reinforce the joint thus formed by plates overlapping at the heel of the stick, tapered transversely in a direction reverse to the transverse tapering of the parts under the plates.

A further purpose is to provide a morticed and tenoned joint at the immediate junction of the handle and blade of a hockey stick, and to reinforce this joint with laminations consistent with the ultimate contour of the finished stick and blade blending with the adjacent upper portions of the handle and outer portions of the blade.

A further purpose is to use a morticed and tenoned joint adjacent to the heel of a hockey stick in connection with reduced exterior portions of both, which shall exteriorly taper in excess of the normal taper of the adjacent parts of the handle and blade, and to make up for or supplement the excessive taper of this portion of the joint of reduced thickness, extending from the heel into both the handle and the blade, by laminations at this point, which conform the outside of the laminations with or to the normal contours of the handle and blade.

This invention completely eliminates the costly and wasteful method of bending more generally employed, which method always distorts the grain of the wood, destroying its original strength and producing a stick subject to warp and change, particularly in the angle of relationship of the blade to the handle of the hockey stick.

This invention insures a constant, predeter-

2

mined angle relationship of the blade to the handle as may be desired, and allows the selection and use of the best quality materials suitable for hockey stick manufacture, and produces a hockey stick of more or less resilience or spring and balance as may be desired.

I prefer to illustrate my invention by one form only, selecting a form which is light, strong and effective and which at the same time well illustrates the principles of my invention.

Figure 1 is a fragmentary side elevation of the lower part of a completed hockey stick showing the entire blade and the lower portion of the stick.

Figure 2 is a top plan view of the construction seen in Figure 1.

Figure 3 is a fragmentary rear end elevation of the structure of Figure 1.

Figure 4 is a bottom plan view of the structure of Figure 1.

Figure 5 is a disassembled view of the several parts in separated positions ready for connection together to assemble the finished stick.

Figure 6 is a section upon line 6—6 of Figure 1.

25 In the drawings similar numerals indicate like parts.

Broadly, in this invention separate handle shaft and blade parts are morticed together at the lower end of the handle shaft. A tongue or tenon is located on the heel end of the blade and extends upwardly into the shaft. To further strengthen and to provide a more durable joint and heel area, a recess is provided on each side of the hockey stick handle and blade, extending 30 along a straight line from approximately the center of the sole of the blade to a point on the handle shaft. Into these recesses are permanently placed laminations, one on each side or face, which laminations have the grain of the wood running parallel to their longest sides, thus 35 crossing grain in the handle shaft as well as crossing grain in the heel area of the blade of the hockey stick. This method of construction permits the use of any desired angle of the blade 40 to the handle shaft and permits any blade width as may be preferred.

The laminated construction has many advantages; in that it not only gives the normal strength due to crossed grains indicated above, 45 present in every laminated structure, but it gives opportunity to use the best or most available type of wood or pieces of wood for the handle and blade, respectively, without first having regard for the capacity of the wood for standing up against blows, and to take care of the

resistance-to-impact factor by special selection of the laminations applied on opposite sides of the joint and by the strength given to the laminations. Each of these laminations will be relatively thin at the neck, between the blade and handle, and progressively thicker as it approaches the heel.

The tapering of the walls of the lower end of the handle about the mortice slot, progressively thickening from the back to the front, are just the opposite of those which are desirable—if there is to be a taper—in the finished joint; and this reversed taper is provided in order to permit a considerable taper, progressively becoming thicker front to back in the laminations upon the sides of the joint.

The tapers of the laminations may be just sufficient to overbalance the reversed taper given by the mortice wall, where the over-all thickness is intended to be uniform or, may underbalance this taper or overbalance it, according to the direction and extent of taper of cross section intended in the final joint.

The inserts fitted within the recesses (i. e., the laminations at opposite side faces) will ordinarily be slightly thicker than is ultimately intended in the finished stick so as to allow for the final contouring of the joint, blade and adjacent part of the handle.

The handle 8 is tapered as usual from some point 8' and the taper is carried down through the joint between the handle and the blade, into the blade and out to the toe of the blade. The lower end 9 of the handle is carried down to the heel 10 at the rear of the joint between the handle and the blade.

The lower end 9 of the handle is morticed at 11 for a tenon 12 at the rear end of the blade, and this tenon extends rearwardly within the mortice and upwardly to such an extent that its upper end 13 reaches approximately to the upper end of the curve 14 upon the front and upper surface of the handle and blade at their junction. The two are glued together with any suitable laminating glue.

The mortice is preferably, though not necessarily, of uniform thickness across the space between the side members. The parts of uniform thickness may be glued together preliminarily to the gluing of the rest of the joint, or this gluing can be effected at the same time as the application of laminations to the outside of the joint, and with the same type of glue. In either case both parts of the gluing may be produced under the most favorable conditions of pressure, with or without heat and with or without waterproofing.

Not only do the handle near the blade and the blade taper longitudinally, progressively reducing in size toward the blade and toward the toe end of the blade, as indicated, but from a location about the rear end of the blade and approximately at the heel 10 to the end of the blade, the blade part is thickened toward the sole as compared with the thickness at the top.

In other words, the top of the blade, from the throat area to the toe is preferably thinner than is the blade at the heel and at the sole. Part of this reduction in thickness of the top as compared with the heel and sole occurs through sanding but there should be a definite slope rearwardly and downwardly, the sides diverging from the top of the blade toward the sole.

Though it is permissible to have a taper in transverse direction upon the lower portion of

the handle, this does not have the same importance as the taper in the blade, and the sides of the handle may be parallel.

The sides of the lower part of the handle and 5 of the blade blend one into the other, from the throat and through the lower part of the handle and the blade immediately adjacent to the heel, and extending out into the sole.

The initial joint between the handle and the 10 blade is of course that between the sides of the mortice and tenon, in which the grain of the walls of the mortice is at an angle whose degree will be different for different sticks, with the grain of the tenon, forming a three-ply laminated structure capable of being glued separately under pressure and forming a strong initial joint. However, I find it very desirable to reinforce this 15 joint by two opposite outside laminations having the grain of each across the grains of both 20 the handle and blade. These laminations are glued to the floors of recesses in the opposite sides of the joint, forming a five-ply laminated structure not only at the heel but throughout the 25 entire section occupied by the mortice and tenon joint. This has various advantages. It not only generally reinforces the mortice and tenon joint but it can be carried above the mortice into the adjacent handle section and forward toward the toe in the blade beyond the tenon, to give a cross 30 lamination tie at the heel and about the entire joint. It also permits the use of a wood which is better suited to stand impacts than is the wood of either handle or blade, for a protecting outer cover for the joint.

35 In placing the laminations, the recesses in the lower end of the handle and the rear portion of the blade are cut to a depth sufficient to give a thicker lamination at the heel than at the throat, the surface of the recess extending 40 from a point in the rear of the handle preferably above the mortice portion and extending continuously across the outside walls of the mortice and across the adjacent part of the blade to the sole of the blade.

45 The bottom surfaces or floors of the recesses in the lower part of the handle and in the blade lie within a single plane such that the laminating surface intended to fit in may also be formed as a plane which will unite to the best advantage continuously with the bottoms of the merging recesses.

50 As the laminations 15 are exposed at the heel edge at 10' in a projecting angle, where they sandwich the tenon heel 10², it is desirable that 55 they be relatively thick at this heel. There is not quite so great need of thickness in the laminations along the throat edge, containing the curved surface 14'. To take care of this to the best advantage, the laminations are tapered transversely from some such zone as the throat to the heel angle at 10'. This again is relatively a refinement by which the structure is considerably improved but which could be omitted while retaining a very desirable laminated joint.

60 In the middle of the blade and in its outer parts, a definite taper is shown from the top toward the sole, the blade progressively becoming thicker as the sole is approached. Because of the "sanding" operation there will usually be a greater reduction of thickness at the immediate top than is justified by the general taper of the parts.

65 The walls 16 of the lower end of the handle 70 embrace the tenon at the rear of the blade 17 where the blade has been cut away to form

shoulders or edge faces tapering from 18 to 18'.

The mortice and tenon joint not only slopes lengthwise of the stick, but slopes from the rear 19 of the handle forwardly, becoming progressively thicker forwardly. At the front edge they correspond with the edge faces from 18 to 18'. The blade may or may not be of uniform thickness or slope at the joint but in the main, slopes from its thinner top edge 20 toward the thicker sole 21.

In the finished stick the slope of the handle ends about the mortice is balanced or overcome in the laminations applied on opposite faces.

The taper of the sides about the mortice is balanced or approximately balanced in the illustration by the oppositely directed taper of the laminations. The efforts from the two tapers do not interfere with the preferred uniform thickness of the tenon.

The cutting away of the blade at opposite faces to produce the tenon leaves shoulders 22, which are higher at 23 than at 24.

The lateral surfaces of the handle about and adjacent to the mortice and that portion of the blade beyond the tenon are recessed at 25 and 26, leaving the shoulders 21 and 28. The floors 29 and 30 of the recesses are in the same plane.

So far as the construction is concerned the question of whether the joint and adjacent parts of the handle and blade ultimately are thicker at the rear portion of the stick or the lower portion of the blade (sole) than at some other part of the joint, or at the top or front of the blade or handle at some other part is a matter of policy in construction of the stick—usually a matter of balance, or of preference or whim on the part of the hockey players for whose use the sticks are intended. My method of construction and the character of stick thus completed are capable of adaptation to any such need or preference.

The recesses not only extend upwardly into the handle beyond the mortice so as to avoid having the end of the laminations against the shoulder coincide with the end of the mortice, but forwardly into the blade so as to avoid having the end of the laminations there coincide with the front end of the tenon. The floors 29 and 30 of the recesses merge, one with the other, so as to require single laminations only to unite with both floors, in a joint whose strength is greatly improved by extension of the laminations up into the handle above the mortice and forwardly into the blade beyond the tenon.

Of course, the initial joint between the handle and blade is secured by the mortice and tenon, which themselves give three laminations having wood grains at angles to each other, varying in grain angle with the angle made by the blade with respect to the handle in the particular stick in question. This angle varies considerably.

Throughout the mortice and tenon section the number of laminations is increased by the laminations upon the outside of the joint, so that, in the joint area there are five laminations. Beyond the mortice and tenon joint, up into the handle and forwardly into the length of the blade, the body of the handle and the blade are laminated by the outside plates only giving the three layers within these sections, with a smaller angle between the grain directions than in the mortice and tenon joints but the same difference in grain directions that are present between the

laminating layer and the outside of the handle at the joint.

It will be understood that a definite policy of taper and direction of taper in cross sections through the joint and through the blade will be maintained in contouring the stick, but that this policy as a policy will yield somewhat to variations in contour due to sanding which will relieve or alter the tapers adjacent the edges and because of the balance which must be secured in order that the stick may "feel" right. This depends in part upon the "balance" of the stick itself and in part upon the idiosyncrasies of the intending user.

15 It will be evident that the stick, as described, is sturdy, effective, capable of adjustment to any of the needs of service so as to satisfy the most exacting player and capable of exact balance by variations in the proportions of the different features present.

20 In view of my invention and disclosure variations and modifications to meet individual whim or particular need will doubtless become evident to others skilled in the art, to obtain all or part of the benefits of my invention without copying the structure shown, and I, therefore, claim all such insofar as they fall within the reasonable spirit and scope of my claims.

Having thus described my invention what I claim as new and desire to secure by Letters Patent is:

1. In a hockey stick, a blade having a tenon, and a handle tapered lengthwise toward a joint with the blade, the handle being morticed and glued to the tenon of said blade to form a joint, and laminations conforming and glued to a recessed surface of the handle outside the mortice and to a recessed portion of the blade adjacent to the tenon.

2. A laminated joint for the handle and the blade of a hockey stick, comprising a mortice and tenon glue joint and laminations over and outside the mortice and tenon area and extending up on to the handle and down on to the blade on both lateral sides of the joint and glued to the handle and blade, the handle end of the mortice and tenon joint being tapered to progressively reduce in thickness toward the lower end of the handle and to progressively reduce in thickness from the front of the handle to the rear of the handle and the laminations progressively increasing in thickness from the front of the joint to the heel of the blade, and at opposite ends extending repetitively into recesses within opposite side faces of the handle and opposite side faces of the blade.

3. In a hockey stick, a handle and blade having mortice and tenon glue union between them and recessed surfaces on the outsides of the handle and blade adjacent the tenon, the mortice portion at the joint tapering from greater thickness at the front face of the handle to a lesser thickness at the rear face of the handle and from a greater thickness at the handle edge of the mortice to a lesser thickness at the blade edge of the mortice and laminations fitting within the recesses in the outer surfaces of the handle and blade across the joint, the laminations tapering from a lesser thickness at the front of the joint to greater thickness at the heel of the joint, and laminating glue holding the laminations to the handle and blade across the joint.

4. In a hockey stick, a handle and blade having mortice and tenon glue union between them and recessed surfaces on the outside of the mortice,

on the handle adjacent the mortice and on the blade adjacent the tenon, the mortice tapering from a greater thickness at the front of the handle to a lesser thickness at the rear of the handle and from a greater thickness at the handle to a lesser thickness at the edge of the blade and laminations fitting within the recesses in the outer surfaces of the mortice, reversing the taper at the mortice from front to back of the handle, and laminating glue holding the laminations to the stick and blade across the joint.

5. In a hockey stick, a handle portion cut to form a mortice whose walls progressively reduce in thickness from the longitudinal side toward the blade to the opposite longitudinal side, and from the handle end of the mortice toward the heel of the stick, a blade, a tenon carried by the blade, fitting into and glued into the mortice, there being recesses in the handle on each side of the mortice and extending beyond the mortice toward the grip end of the handle, there being recesses in the blade on each side of the tenon and extending away from the heel with respect to the tenon, the longitudinal walls of the recesses in the handle and in the blade at each side of the stick forming a flat surface, and laminations in the recesses outside of the mortice, uniting and glued to the longitudinal walls of the recesses, and extending beyond the tenon along the blade and back of the mortice along the handle, the

5

10

15

20

30

grain in the laminations extending at an angle to the grains in both the handle and the blade.

6. A laminated joint for the handle and the blade of a hockey stick, comprising a mortice and tenon glued joint and laminations outside the mortice and tenon area and extending up on to the handle and down on to the blade on both lateral sides of the joint, beyond the joint at each end, and glued to the handle and blade, the portion of the mortice and tenon joint integral with the handle being tapered progressively to reduce in thickness toward the lower end of the handle and to progressively reduce in thickness from the longitudinal side of the handle toward the blade to the opposite longitudinal side of the handle, the laminations fitting in recesses of the handle and blade whose longitudinal walls form a flat surface and the laminations themselves being tapered to conform to the taper of the blade and handle.
